VENETIAN BLIND STRUCTURE

Harry H. Nelson, New York, N. Y., assignor to
 Lorentzen Hardware Mfg. Corp., New York,
 N. Y., a corporation of New York

Application July 29, 1944, Serial No. 547,115

17 Claims. (Cl. 160—177)

My invention relates to improvements in Venetian blinds and has to do, more particularly, with supporting means for the tilt bar commonly forming a part thereof.

It has been the practice, in the case of Venetian blinds of considerable extent, i. e., blinds having relatively long slats or having a large number of slats, or both, to support the tilt bar at a point or points between its ends, as well as at said ends. Such supplemental support for the tilt bar has as its purpose the elimination of the tendency of the bar to sag downwardly, intermediate its terminal supported portions, which tendency is objectionable from the standpoint not only of appearance but also in many instances, from the standpoint of secure, smooth and easy tilting of the slats.

Supplemental supports for this purpose are generally known in the art as "center supports" and a number of designs thereof have been proposed, for example that disclosed in the patent of H. K. Lorentzen, No. 2,120,284, granted June 6, 1938. In a sense, the present invention may be regarded as an improvement upon the device of that patent, affording a number of important advantages thereover.

Having in mind the characteristics of the devices of the prior art, my invention may be said to have, as its primary object, the provision of a supplemental support for the tilt bar of Venetian blinds which support is of greater structural and functional simplicity than any hitherto developed.

It is another object of my invention to provide a supplemental support for Venetian blind tilt bars which consists of only two parts; one for rigid attachment to the head rail of the blind, the other for rigid attachment to the tilt bar; the linkage of said two parts being of a simple pivotal nature.

It is a further object of my invention to provide a supplemental support for Venetian blind tilt bars wherein accurate support is inherently assured at any and all tilted positions.

It is a still further object of my invention to provide a supplemental support for Venetian blind tilt bars which is capable of being quickly and easily coupled and uncoupled to facilitate installation of the blind and to enable easy detachment of the tilt bar and its slats for either window or blind cleaning.

It is also an object of my invention to provide a supplemental support for Venetian blind tilt bars which is inexpensive to manufacture and

which may be installed with a minimum of expense for labor.

Further objects and objects relating to details and economies of construction and operation will more definitely appear from the detailed description to follow.

My invention is clearly defined in the appended claims. In the claims, as well as in the description, parts are identified by specific names for convenience, but such nomenclature is intended to be as generic, in its application to similar parts, as the prior art will permit. The best form in which I have contemplated applying my invention is illustrated in the accompanying drawings forming part of this specification, in which:

Fig. 1 is a front view, in elevation, illustrating a tilt bar structure which embodies the present invention in supporting means therefor, a portion of the structure being shown in section so as to reveal the character of the tilt-bar-attached part of the supporting means;

Fig. 2 is a vertical cross-sectional view showing the center portion only of the tilt bar and head rail of the structure depicted in Fig. 1, the view being taken on the line 2—2 thereof;

Fig. 3 is a detail horizontal cross-sectional view of the central portion of the tilt bar, the view being taken on the line 3—3 of Fig. 1;

Fig. 4 is a perspective view of the center support, per se, of the structure illustrated in Fig. 1;

Fig. 5 is a view, in front elevation, of the center portion only of a head rail and tilt bar provided with tilt bar supporting means constituting another embodiment of my invention;

Fig. 6 is a vertical sectional view of the structure shown in Fig. 5, the view being taken on the line 6—6 thereof;

Fig. 7 is a bottom plan view of the portion of the tilt rail shown in Fig. 5; and

Fig. 8 is a perspective view of the center support, per se, of the structure illustrated in Figs. 5, 6 and 7.

Similar characters of reference refer to similar parts throughout the several views.

In a broad sense, my invention may be said to consist in the provision of a center, or otherwise non-terminally located supplemental support for the tilt bar of a Venetian blind which support consists essentially of two hingedly-coupled parts; one rigidly mounted upon the head rail of the blind and the other rigidly mounted on the tilt bar thereof. The head-rail-attached part has the general character of a depending bracket terminating in a hook which receives and supports a pintle portion of the tilt-rail-attached

part, which pintle portion is accurately located on the rotative axis of the tilt bar. The tilt rail is notched-out or otherwise relieved at the zone of such supplemental support and the clearance thus afforded the bracket, in conjunction with the offset character of the bracket itself, enables rotation of the tilt bar an extent amounting to as much or more than the 180° range desirable therefor without resort to such expedients as the sliding connections or otherwise complicated articulated linkage characteristics of the prior art. A certain amount of flexibility is inherent in terminally supported tilt bars having an extent such that supplemental support therefor is required and, in accordance with the concepts of the present invention, this flexibility is utilized to advantage by reliance thereon to enable normal springing of the aforesaid tilt-bar-carried pintle into and out of assembly with the hook of the head-rail-carried bracket.

Referring now to the accompanying drawings, I have illustrated in Figs. 1 through 4 thereof what I regard to be the best form of my invention from the standpoint of simplicity. In Fig. 1 is depicted a conventional head rail 10 of wood or the like (shown shortened by breaking out portions thereof) which head rail carries the usual cord-operated tilter mechanism (referenced generally by the numeral 11) and end bracket 12, by and between which parts 11 and 12 the tilt bar 13 (also usually of wood and here shown broken out to permit condensed illustration) is terminally supported for rotation. To this tilt bar 13 are attached the usual slat-supporting tapes of the blind proper (not shown). As is well known, when the blind is of considerable extent (for example having slats and tilt bar more than three feet in length, or having a large number of slats which impose such a burden upon the tilt bar 13 that the support at 11 and 12 is inadequate to carry the load with security and without appreciable depressed bowing of the intermediate portion of tilt bar) additional support is desirable.

In accordance with the concepts of my invention as embodied by the structure shown in Figs. 1 to 4, such supplemental support is effected through the use of two simple parts; a bracket 14 provided with a base 14a secured by conventional wood screws 14b to the under face of the head rail 10 toward its rear edge, and a W-shaped staple 15 driven into the body of the wood tilt bar at such position, and to such extent, that the central bight portion 15a thereof lies on the axis of rotation of the tilt bar 13 and is receivable as a pintle within the hook 14c of the head-rail carried bracket. As is clearly evident in Fig. 2, the tilt bar 13 is cut out (from its rear edge) for approximately $\frac{3}{5}$ its width, affording clearance for the bracket 14 depicted further in Figs. 1 and 3. In the case of a tilt bar of wood, this "relief" or clearance can be readily effected by means of a wide saw cut. In the case of a metal tilt bar (not shown), it may be desirable to provide the clearance gap in conjunction with the blanking operation performed to fabricate the bar, in which event the pintle portion 15a of the support can be provided as a homogeneously integral portion of the bar itself, either by welding or by a blanking operation.

While a single supplemental support such as depicted in Figs. 1 through 4 normally would suffice, centrally-installed, to maintain the tilt bar against sagging under the burden of supporting a long and heavy slat assembly, under some

circumstances it may be found desirable to employ two or more such bracket-and-pin assemblies along the span of the tilt bar. In the case of such a multiple installation, the supports can be distributed along the full extent of the tilt bar, preferably at positions between the several tape strings suspended therefrom to carry the slats of the blind proper.

In Figs. 6 through 8 of the drawings, I have disclosed another embodiment of my invention which differs from that illustrated in Figs. 1 through 4 principally in respect to the character of the tilt-bar-carried element which is impaled upon the hook of the head-rail-carried bracket. 15 This bracket, denoted by the numeral 114, is of simple L shape, the base portion 114a of which is secured to the head rail 110, adjacent its rear edge, by conventional wood screws 114b. The lower end of the bracket terminates in a hook portion 114c which is forwardly offset with respect to the base portion 114a so as to lie directly beneath the axis of rotation of the tilt bar 113. The tilt bar 113 is relieved to a somewhat greater extent than is that illustrated in the first-25 discussed embodiment of my invention, which relief may be effected therein, in the case of a wood tilt slat or bar, by means of a conventional dado saw. Upon the under face of the thus-notched tilt bar 113 is secured, as by wood screws 115c, 30 the plate member 115 which conforms to the slotted configuration of the bar 114 and is formed with an integral staple-like structure 115a, 115b which is received within the slot of the tilt bar. The pintle portion 115a of this structure lies along 35 the rotative axis of the tilt bar and is received within the hook formation 114c of the head rail bracket, affording support for the tilt bar from said head rail. From an inspection of the character of the bracket 114 and the slot provided 40 in the tilt bar, as illustrated in Fig. 6, it will be manifest that a full 180° rotation of the tilt bar is enabled without resort to reliance upon the complicated articulated bracket structures of the prior art.

45 The mode of use of the structures herein disclosed as illustrative of the concepts of my present invention, as well as the advantages inherent thereto, should be readily understood. In each instance there is a pintle element which substantially bridges the slot of the tilt bar and which is located on the approximate axis of bar-rotation. The hooks 14c and 114c are each set forward of the brackets proper 14 and 114, respectively, so as to afford a minimum of interference with the bar in its tilting rotation. Accordingly, it is possible to provide clearance for these brackets by a slot extending not much more than half-way through the tilt bar. In each instance, some strengthening of the slotted tilt bar against lateral and torsional flexure is afforded by the pintle structures of Figs. 1 and 5, although the plate 55 115 of the latter embodiment is most effective in this respect. Actual experience, however, has shown that either structure is entirely adequate for general use. Likewise, it may be pointed out that although for most installations a single supplemental support of the forms herein disclosed and claimed will suffice for general purposes when provided midway between the tilt bar ends, two or more such structures may be employed if desired. Attention is called to the difference in shape which distinguishes the bases 14a and 114a of the illustrated brackets 14 and 114, respectively, and to the fact that the former is susceptible of production with little or no additional

blanking stock even though means are provided thereby for lateral support at each side of the depending hook-carrying portion thereof. Preferably, each of the parts which comprises the supplemental supports herein illustrated are fabricated from inexpensive sheet metal, the W-shaped member 15 being a simple punching. By reliance upon the inherent flexibility of the tilt bars 13 and 14, it is possible to effect manual hooking and unhooking of the pintle to the bracket without resort to special fastening means or tools. Other features of advantage for my invention, not herein particularly stressed, will appear to those in the Venetian blind art upon familiarization with the general principles thereof. I therefore regard my invention broadly, as indicated by the appended claims, and I wish it understood that the terms employed in each said claim are to be given their broadest possible meaning consistent with their application to the concepts of my invention as distinguished from the prior art pertinent thereto.

What I claim is:

1. A tilt bar structure for Venetian blinds, comprising: a head bar, a tilt bar journaled for rotation adjacent said head bar, a pintle set in said tilt bar between its ends and on its axis of rotation, and a rigid bracket rigidly secured to said head bar and extending therefrom in the form of a hook receptive of and supporting said pintle.
2. A tilt bar structure for Venetian blinds, comprising: a head bar, a tilt bar journaled for rotation adjacent said head bar, a slot provided in said tilt bar between its ends, a pintle in said slot, said pintle lying on the axis of rotation of said tilt bar, and a rigid bracket rigidly secured to said head bar and extending therefrom in the form of a hook receptive of and supporting said pintle.
3. A tilt bar structure for Venetian blinds, comprising: a head bar, a tilt bar journaled for approximately semi-revolutionary rotation adjacent said head bar, a transverse slot provided in said tilt bar, the slot extending more than half-way across the width of said tilt bar, a pintle bridging said slot, said pintle lying on the axis of rotation of said tilt bar, and a rigid bracket rigidly secured to said head bar and extending therefrom in the form of a hook receptive of and supporting said pintle.
4. A tilt bar structure for Venetian blinds, comprising: a head bar, a tilt bar having some degree of flexibility, said tilt bar being terminally journaled for approximately semi-revolutionary rotation adjacent said head bar, and means for precluding intermediate sagging of said tilt bar under the load to which it is intended to be subjected, said means comprising a transverse slot provided in said tilt bar, the slot extending more than half-way across the width of said tilt bar, a pintle bridging said slot, said pintle lying on the axis of rotation of said tilt bar, and a rigid bracket rigidly secured to said head bar and depending therefrom in the form of a hook receptive of said pintle and restraining said tilt bar against intermediate sagging under load, said pintle being initially engageable with said hook portion by simple manually-induced bowing of the intermediate portion of said tilt bar.

5. A tilt bar structure for Venetian blinds comprising: a head bar, a tilt bar having some degree of flexibility, said tilt bar being terminally journaled for approximately semi-revolutionary rotation adjacent said head bar, and means for precluding intermediate sagging of said tilt bar un-

der the load to which it is intended to be subjected, said means comprising a transverse slot provided in said tilt bar, said slot extending substantially half-way across the width of said tilt bar, a pintle in said slot, said pintle lying on the axis of rotation of said tilt bar, and a rigid bracket rigidly secured to said head bar and depending therefrom at the rear of the axis of rotation of said tilt bar, the bracket having a forwardly-directed terminal hook portion extending beneath said axis of rotation and supporting said pintle, and restraining said tilt bar against intermediate sagging under load.

6. A tilt bar structure for Venetian blinds, comprising: a head bar, a tilt bar having some degree of flexibility, said tilt bar being terminally journaled for approximately semi-revolutionary rotation adjacent said head bar, and means for precluding intermediate sagging of said tilt bar under the load to which it is intended to be subjected, said means comprising a slot provided in said tilt bar, said slot extending substantially half-way across the width of said tilt bar, a pintle in said slot, said pintle lying on the axis of rotation of said tilt bar, and a rigid bracket rigidly secured to said head bar, the bracket depending from said head bar at the rear of the axis of rotation of said tilt bar, the bracket having a forwardly-directed terminal hook portion extending beneath said axis of rotation, the hook portion supporting said pintle, and restraining said tilt bar against intermediate sagging under load, said pintle being initially engageable with said hook portion by simple manually-induced upward bowing of the intermediate portion of said tilt bar.

7. A tilt bar structure for Venetian blinds, comprising: a head bar, a tilt bar journaled for rotation adjacent said head bar and provided with a slot extending substantially half-way across the width thereof at a location remote from its ends, a rigid bracket rigidly secured to said head bar and depending therefrom in the form of a hook portion extending beneath said axis of rotation, and a member fastened to said tilt bar and bridging the said slot therein, said member having a pintle portion in said slot on the axis of rotation of said tilt bar and received within the hook portion of said bracket to restrain said tilt bar against intermediate sagging under load.

8. A tilt bar structure for Venetian blinds, comprising: a head bar, a tilt bar journaled for rotation adjacent said head bar and provided with a slot extending substantially half-way across the width thereof at a location remote from its ends, a rigid bracket rigidly secured to said head bar and depending therefrom in the form of a hook portion extending beneath said axis of rotation, and a pronged staple bridging the slot in said tilt bar, said staple having a bight portion set in said slot on the axis of rotation of said tilt bar, said bight portion being engaged with the hook portion of said bracket to restrain said tilt bar against intermediate sagging under load.

9. A tilt bar structure for Venetian blinds, comprising: a head bar, a tilt bar journaled for rotation adjacent said head bar and provided with a slot extending substantially half-way across the width thereof at a location remote from its ends, a rigid bracket rigidly secured to said head bar and depending therefrom in the form of a hook portion extending beneath said axis of rotation, and a W-shaped staple driven into the material of said tilt bar at each side of the slot therein-provided, the staple having an intermediate portion set in said slot on the axis of rotation.

tion of said tilt bar and engaged with the hook portion of said bracket to restrain said tilt bar against intermediate sagging under load.

10. A tilt bar structure for Venetian blinds, comprising: a head bar, a tilt bar journaled for rotation adjacent said head bar and provided with a slot extending substantially half-way across the width thereof at a location remote from its ends, a rigid bracket rigidly secured to said head bar and depending therefrom in the form of a hook portion extending beneath said axis of rotation, and a W-shaped staple driven into the material of said tilt bar from its under face, said staple bridging said slot and strengthening said tilt bar torsionally, and said staple having an intermediate portion set in said slot on the axis of rotation of said tilt bar and engaged with the hook portion of said bracket to restrain said tilt bar against intermediate sagging under load.

11. A tilt bar structure for Venetian blinds, comprising: a head bar, a tilt bar journaled for rotation adjacent said head bar and provided with a slot extending substantially half-way across the width thereof at a location remote from its ends, a rigid bracket rigidly secured to said head bar and depending therefrom in the form of a hook portion extending into the slot of said tilt bar beneath said axis of rotation, a plate member secured to the under face of said tilt bar to increase the resistance thereof to torsional and lateral flexure in the region of said slot, and a pintle set in said slot on said axis of rotation and engaged with the hook portion of said bracket to restrain said tilt bar against sagging under load.

12. A tilt bar structure for Venetian blinds, comprising: a head bar, a tilt bar journaled for rotation adjacent said head bar and provided with a slot extending substantially half-way across the width thereof at a location remote from its ends, a rigid bracket rigidly secured to said head bar and depending therefrom in the form of a hook portion extending into the slot of said tilt bar beneath said axis of rotation, a plate member secured to the under face of said tilt bar to increase the resistance thereof to torsional and lateral flexure in the region of said slot, and a pintle portion integral with said plate member

and disposed within said slot for engagement with the hook portion of said bracket to restrain said tilt bar against sagging under load.

13. A tilt bar for Venetian blinds comprising: a flat slat of non-metallic material having the general characteristics inherent to wood, said slat having a transverse slot therein at a position remote from its ends, said slot extending substantially half-way across the width of said tilt bar, and a staple-like member driven into the material of said slat from its under face and bridging the slot therein, said staple-like member having a pintle portion thereof located on the longitudinal axis of rotation of said slat.

14. A fitting for providing a Venetian blind tilt bar with a supporting pintle between the ends of the bar, said fitting comprising a unitary one-piece staple substantially W-shape in form, the outside legs of the W-formation being drive-in prongs for attaching the fitting to a tilt bar, and the center bight portion of the W-formation being formed as a pintle.

15. A fitting as in claim 14 in which the four legs of the W-formation are parallel to each other and are connected together collectively by three portions disposed perpendicularly to the legs.

16. For a Venetian blind having a head bar and a tilt bar, a fitting for supporting the tilt bar between its ends, said fitting comprising: a plate to be positioned flatwise against the bottom of the head bar and be secured thereto, a flat arm rigid with the plate and extending downwardly and forwardly, the plane of the arm being perpendicular to the plate, and the arm terminating in a hook spaced vertically from the plate by a distance substantially equal to the spacing between the head bar and the axis of rotation of the tilt bar; and a member to be attached to the tilt bar, said member having a pintle portion detachably engageable with said hook, said pintle portion being positioned at the axis of rotation of the tilt bar when the member is attached thereto.

17. A fitting as in claim 16 in which the member to be attached to the tilt bar is a W-shaped staple.

HARRY H. NELSON.
